UNITED STATES PATENT OFFICE.

AUGUST HOLMQUIST AND WILLIAM A. BJORKLUND, OF HOOPESTON, ILLINOIS, AS
SIGNORS TO SPRAGUE-SELLS CORPORATION, OF HOOPESTON, ILLINOIS, A CORPORA-
TION OF DELAWARE.

FINISHING MACHINE.

Original application filed February 14, 1924, Serial No. 692,716. Divided and this application filed October 3, 1924. Serial No. 741,336.

To all whom it may concern:

Be it known that we, AUGUST HOLMQUIST and WILLIAM A. BJORKLUND, citizens of the United States, residing at Hoopeston, in the 5 county of Vermilion and State of Illinois, have invented new and useful Improvements in Finishing Machines, of which the following is a full, clear, concise, and exact description, reference being had to the accompanying drawing, forming a part of this specification.

Our invention relates to screens and more particularly to devices of this type employed to separate the pulpy liquid from the 15 heavier material containing crushed seeds, pieces of skin, etc., of the pulp run through pulping and finishing machines.

In finishing machines such as we have disclosed in our co-pending application, 20 Serial No. 692,716, filed by us on February 14, 1924, patented November 11, 1924, #1,515,113 a series of symmetrically arranged brushes rotate with respect to the screen at a pre-determined distance so that 25 the heavier material will work away from the screen and not be forced through the perforations. Like the remaining parts of the machine, we have found it desirable to construct the screen in a manner permitting 30 renewal, not only of the entire structure, but also of sections which are apt to wear or be damaged. In our co-pending application, we have disclosed, in connection with the finishing machine, an improved screen 35 capable of being renewed in part or in whole. The present application is a division of our co-pending application and is directed particularly to the subject matter of said screen.

According to the construction disclosed herein, if a portion of the screen is punctured or worn, only such portion need be renewed. This is an important feature in that it accomplishes a remarkable saving in the 45 maintenance cost of the machine. Moreover, very little time is required in making substitution of the new part, as provision is made for assembling the sections and holding them in a unitary rigid relation.

In order to apprise those skilled in the art how to construct and practice our invention, we shall now describe an embodiment thereof in connection with the accom-

panying drawing which forms a part hereof.

In the drawings:

Figure 1 is a top plan view of a screen embodying our invention, being partly broken away to illustrate the manner of joining the sections together;

Fig. 2 is a side elevation of the same;

Fig. 3 is a horizontal section through the screen, this view being on a smaller scale than Figures 1 and 2;

Fig. 4 is a detailed sectional view through the screen at a point where the sections thereof are joined together;

Fig. 5 is a detailed sectional view of the screen taken through the upper portion thereof; and

Fig. 6 is a fractional view of the bottom portion of this screen.

By referring to the drawings, it will be noted that the screen comprises four sections 5, 6, 7 and 8. As illustrated in Figure 4, the adjacent edges of, say, sections 5 and 6 are overlapped into an interlocking fold, with a channel member 9 for embracing the folded portions and securing the same together. The channel members 9 are preferably made of a metal which allow said channel members to be pressed about the fold and to be held in this position without the provision of other securing means. We could, however, employ bolts, or the like, 85 for locking the channel in place, but with the present arrangement, the use of bolts is unnecessary.

By referring to Figure 5 it will be noted that the upper circumferential edge of the 90 screen is held clamped between an upper ring 10 and a lower ring 11, these rings being suitably secured together, say by bolts 12. A similar arrangement is provided at the lower edge of the screen. As shown in 95 Figure 6 a casting 14 comprises the bottom of the screen, and about this casting 14 an annular retaining ring 15 is bolted by means of bolts 16. This retaining ring 15 clamps the lower edge of the various screen sections 100 against an inclined face 17, formed on casting 14. Reinforcing rods 18 are employed between the upper and lower edges of the screen to hold the latter rigidly extended. These rods at their upper end thread into 105 suitable brackets 19, bolted at 20 to the

lower clamping ring 11. At the lower end, the reinforcing rods 18 pass through apertured lugs 21 on the annular retaining ring 15. Nuts 22, or other suitable means, may 5 be used for holding these lower ends in the lugs 21.

From the foregoing description, it will be observed that we have provided an improved form of screen which, while illustrated as conically formed, may have any other desired shape or configuration, such as may be required for the particular machine into which it is to be fitted. The finishing machine disclosed in our co-pending 10 application has been provided with a downwardly swinging pivotally mounted bowl into which the screen is inserted. In this prior machine, an annular recess is furnished which is closed on three sides so as 15 to receive the annular projecting edge 25 of the upper rings 10 and 11. We have found this arrangement to be a unique way of suspending or providing a mounting for the screen. We wish it to be understood, 20 however, that the screen may be mounted in any desired way, and that we do not desire to be limited in this respect by our prior disclosure. We stress this point because those skilled in the art may readily 25 realize the advantages of a sectional screen such as we disclose herein, and the possibilities of adopting this construction in a horizontal cylindrical screen.

It will be further observed that the clamping 30 means provided by us at the upper and lower ends of the screen are simple and afford easy and rapid removal of any of the sections 5, 6, 7 or 8 when worn, or otherwise damaged, and a new part must be substituted therefor.

Without limiting ourselves to the specific structure herein shown, except as is intended to be defined and secured to us by the following claims;

45 We claim:

1. A perforated screen for a finishing machine comprising a plurality of sections joined along their adjacent edges by an interlocking fold, and provided with means 50 for securing and embracing said fold.

2. A perforated screen for a finishing machine comprising a plurality of sections joined along their adjacent edges by an interlocking fold, and means for reinforcing 55 said interlocking fold.

3. A perforated screen for a finishing machine comprising a plurality of sections

having their adjacent edges interconnected, and including means to which the upper and lower peripheral edges of said sections 60 may be removably secured.

4. A perforated screen for a finishing machine comprising a plurality of interconnected sections, a plurality of longitudinal reinforcing rods for holding said sections rigidly extended, and means for removably gripping the upper and lower peripheral edges of said sections. 65

5. A perforated screen for a finishing machine comprising a plurality of interconnected sections having longitudinal reinforcing means for holding said sections rigidly extended, and means for receiving the upper and lower peripheral edges of said sections permitting removal of one or more 75 of said sections.

6. A perforated screen for a finishing machine comprising a plurality of interconnected sections with reinforcing means to hold said sections rigidly extended, and means for also reinforcing the interconnecting edges of said sections. 80

7. A perforated screen for a finishing machine comprising a perforated body portion and a pair of clamping members at each end for receiving the peripheral edges of said body portion. 85

8. A perforated screen for a finishing machine comprising a perforated body portion, a pair of clamping members at each end for receiving the peripheral edges of said body portion, and reinforcing members extending between said pairs of clamping members for holding said body portions rigidly extended. 90

9. A perforated screen for a finishing machine comprising a plurality of interconnected sections, clamping members at each end for receiving the peripheral edges of said sections, and reinforcing members extending between said clamping members for holding said sections rigidly extended. 95

10. A perforated screen for a finishing machine comprising a plurality of sections interconnected by the adjacent edges thereof being in folded relation with each other, means for securing said folded edges, clamping members at each end of said screen for receiving the peripheral edges thereof, and reinforcing members for holding said clamping members rigidly spaced. 100

In witness whereof, we have hereunto subscribed our names.

AUGUST HOLMQUIST.
WILLIAM A. BJORKLUND.
